W. F. STEWART

WATER HEATER

Filed Dec. 31, 1917

UNITED STATES PATENT OFFICE.

WILLIAM F. STEWART, OF ST. LOUIS, MISSOURI, ASSIGNOR, BY MESNE ASSIGNMENTS,
TO AMERICAN HEATER CORPORATION, A CORPORATION OF DELAWARE.

WATER HEATER.

Application filed December 31, 1917. Serial No. 209,608.

To all whom it may concern:

Be it known that I, WILLIAM F. STEWART, a citizen of the United States, and a resident of the city of St. Louis and State of Missouri, have invented a new and useful Improvement in Water Heaters, of which the following is a specification.

My invention relates to hot water heaters of the kind commonly referred to as instantaneous heaters. In heaters of this type, the flow of gas to the burners is commonly controlled by a thermostat and such heaters are subject to certain disadvantages which it is the object of the present invention to avoid. Most of these disadvantages are occasioned by the fact that the shutting off and the opening up of the gas supply by thermostatic action are quite gradual. In the first place, gradual shutting off of the gas supply disturbs the proper proportioning of the gas and air in the mixing chamber of the burner and thus tends to create a condition liable to cause back-fire. Again, under conditions of full pressure, the mixed gas and air are projected from the burner opening so as to ignite at a distance from the burner, whereas, under lower pressure, the ignition occurs close to the burner and tends to unduly heat the burner and thereby create a condition favorable to back-fire and to the rapid deterioration of the burner. An even more important practical disadvantage is the fact that the closing and the opening action of the thermostat are so gradual that the temperature of the water has a very wide range, whereas it is desirable to maintain a temperature of the delivered water as nearly uniform as practicable. Another common disadvantage of instantaneous water heaters of the type now in use is that it is difficult to adjust them for use under widely varying conditions of pressure in the fuel supply and in the water supply.

The principal objects of the present invention are to overcome the disadvantages hereinbefore mentioned. The invention consists principally in making the valve action quickly responsive to variations in the thermostatic controller; it also consists in making the fuel supply valve open and close by a single quick stroke as distinguished from the gradual opening and closing hereinbefore mentioned; it also consists in means for adjusting and co-ordinating the valves to fit the device for widely different condi-

tions of fuel and water supply; and it also consists in the combinations and arrangements of parts hereinafter described and claimed.

In the accompanying drawings, wherein like reference numerals refer to like parts wherever they occur,

Fig. 1 is a vertical view of part of an instantaneous water heater embodying my invention, being a section through the valve mechanism on the line 1—1 of Fig. 2 and showing the lower portion of the thermostatic controller in elevation;

Fig. 2 is a horizontal view, being a section on the line 2—2 of Fig. 1;

Fig. 3 is a detail view illustrating the connection of the thermostat with the water valve actuating lever, being partly in elevation and partly in section on the line 3—3 of Fig. 2;

Fig. 4 is a horizontal sectional detail on the line 4—4 of Fig. 1, showing the mounting of the water valve actuating lever;

Fig. 5 is a detail of the connection between the main water valve stem and lever that actuates same, the valve stem being in section on the line 5—5 of Fig. 1; and Fig. 6 is a detail view of the lost-motion device.

The present apparatus comprises the usual elements of a water heater of the so-called instantaneous type, such, for instance, as that shown in Patent No. 1,028,146 granted to me June 4, 1912; that is to say, it comprises a gas or vapor burner, a water heater coil arranged in operative relation to the burner, and an inclosing shell or casing 1, together with a novel organization of thermostatically actuated valves for controlling the gas and water supply. In the water supply pipe 2 leading to the coil is the main water supply valve 3, which is controlled thermostatically as hereinbefore described.

This main water supply valve 3 has a hollow cylindrical casing with an inlet opening 4 at its side and an annular groove 5 in its wall opposite said opening. The main delivery port 6 is at one end of the cylindrical valve casing; and this port is of less diameter than the normal diameter of the casing. Inside of the casing is an umbrella shaped valve 7 adapted to seat against the edge of the delivery port 6 and thereby seal the same and having a depending annular marginal portion 8 whose outer surface fits the valve casing below the annular groove therein.

100
105
110

110

The lower margin of the valve is notched in such manner that when the end of the valve is seated against the edge of the main delivery port 6, the inlet port communicates 5 through said notches with the lower portion of the valve casing. The valve is normally held against its seat by means of a helical spring 9 bearing against the under side thereof and against the screw-threaded head 10 of the valve casing. This valve is provided with an elongated stem 11 which extends through the head of the casing and is operatively connected to the thermostatic apparatus hereinafter described so as to be 15 actuated thereby.

Alongside of the casing of the main water valve 3 and preferably made integral with said casing is a cylinder 12 which has ports 13 and 14 at its upper and lower ends 20 which communicate with the upper and lower ends of the valve casing respectively. Inside of said cylinder is a piston 15 whose middle portion 16 is extended beyond the bearing surface of the piston far enough 25 to bear against the end of the cylinder and thereby limit the movement of the piston so that it will not close the communication between it and the lower end of the valve chamber. The upper surface of the piston 30 opposite this projection is concaved or hollowed out to form a chamber 17 which communicates permanently with the lower end of the chamber through ports formed in the limiting extension. Extending upwardly from the piston 15 is a stem 18 whose upper end is screw-threaded and provided with a nut 19. Slidably fitted on this 35 stem is a valve 20 adapted to seat against an annular flange provided therefor on the upper surface of the piston so as to close the communication between the two sides of the cylinder. This valve 20, which is hereinafter referred to as the relief valve, is normally held in closed position by means 40 of the helical spring 22, which bears against it and against the nut 19 provided therefor on the stem, the said nut being adjustable for the purpose of varying the pressure of the spring against said valve. The upper 45 surface of the piston 15 is also provided with concentrically disposed lugs which serve as positioning members for the helical spring 23 which bears at one end against the piston and at the other end against the threaded head 50 55 24 of the cylinder.

The operation of the valve mechanism above described is as follows: Assuming that the main water valve is closed, the water from the inlet port 4 enters the lower 60 portion of the valve casing through the notches in the side of the valve and thence passes into the lower end of the cylinder 12 underneath the piston 15, causing the piston to be moved upwardly against the pressure of the helical spring 23 until the

end of the piston stem 18 comes in contact with the head 24 of the cylinder. This lifting of the piston 15 actuates the gas valve as hereinafter described but does not of itself cause any movement of the main water valve 7. When the thermostat pulls the main water valve 7 down against its spring 9, a direct passage is opened from the inlet port of the valve casing to the outlet port and a supply of water flows 75 through the heater. While this condition continues, water passes from the outlet end of the valve chamber to the upper part of the cylinder and co-operates with the helical spring 23 in tending to force the piston downwardly against the upward pressure of the water on the under side of the piston. When the thermostat causes the closing of the main water valve, the pressure on the upper part of the piston is relieved and the 80 water from the supply pipe again passes through the notches in the valve into the valve casing and thence into the lower end of the cylinder and again lifts the piston. This up-and-down movement of the piston 85 is transmitted to the gas valve as herein-after described.

As illustrated in Fig. 1, the gas supply pipe 25 is provided with a valve case 26 which contains a valve seat with which co-operates a valve 27. This valve is provided with a helical spring 28 which bears at one end against the valve and at the other end against the threaded cap 29 of the valve casing. This valve is also provided with a 90 valve stem 30 which extends through said head and is adjustably connected to the piston rod 31 of the piston 15. A suitable connection between the valve stem or rod 30 of the gas valve 27 and the piston rod 100 31 is illustrated in Fig. 1. As there illustrated, the two rods 30 and 31 are disposed in axial alinement. The meeting ends of the two rods are screw-threaded. Working on the threaded end of the rod 30 of the gas valve is a turnbuckle 32 which is held in adjusted position by means of a locking nut 32a. The piston rod 31 extends through a hole provided therefor in the other end of the turnbuckle and slides 110 freely therein. The screw threaded end portion of this piston rod 31 is provided with a set nut 33 and a lock nut 34 therefor inside of the turnbuckle. This contrivance 115 constitutes an adjustable lost motion connection between the two rods whereby the piston is enabled to move a predetermined distance (which may be varied as desired) without affecting the gas valve and whereby the further movement of the piston is 120 transmitted to the gas valve.

Any suitable thermostatic device for controlling the water supply may be used; but the construction illustrated is especially advantageous. In this connection, the main 130

water supply valve and the gas valve are mounted on a casting 35 which has an extending bracket 36 upon which is mounted the lever 37 that is actuated by the thermostatic element and itself actuates the main water supply valve. This lever has a bifurcated end 38 which straddles the extending stem 11 of the main water supply valve 7 and has the bifurcated portions rounded 10 to rest upon a nut or washer 39 movably mounted on the lower end of the valve stem. The other end of this lever is provided with a knife edge 40 which works in notches constituting bearings therefor in the bracket 15 of said casting. Close to its fulcrum, the lever has a vertically threaded hole therethrough in which works a threaded plug 41 which is provided with a set nut for holding it in adjusted position. The upper 20 end of this plug projects slightly above the lever and is rounded off to co-operate with a rounded stud 42 provided therefor at the lower end of a brass or copper tube 43 forming part of the water delivery pipe system. This copper or brass tube is supported 25 at its upper end in a bracket, which in turn is supported by means of two vertical rods 44 that are mounted on the bracket forming part of the support of the water supply 30 valve and the gas valve. By this arrangement, the water delivered from the heater will cause the copper or brass tube to vary in length according to the variations of the temperature of the water. The parts are 35 so adjustable that when the water is cold and the main water supply valve is closed, the stud 42 on the thermostatic tube does not press against the plug on the lever, although, if desired, it may be in contact 40 therewith. As the temperature of the water delivered from the heater increases, the thermostatic tube elongates and transmits pressure against the lever 37 so as to open the main supply valve and thereby admit 45 water to the upper end of the cylinder 12 and cause the piston therein to move downwardly to close the gas supply valve 26, leaving the valve open for the inlet of water to the heater. The effect of opening 50 the water supply to the heater and of cutting off the supply of gas is to cool the thermostatic tube, which shortens and allows the spring of the main water supply valve to close and shut off the supply of 55 water to the heater and admit water to the under side of the cylinder to lift the piston and thereby open the gas supply valve. This operation is repeated intermittently at such short intervals that the temperature 60 changes of the heated water are inconsiderable.

I claim:

1. In a water heating system, a water supply valve irresponsible to variations of water pressure, a gas supply valve, a thermostat 65

in operative relation to the water supply valve to operate the same, and means for actuating the gas supply valve, said means comprising a cylinder, a piston therein and a rod operatively connecting said piston to 70 said gas supply valve, said water supply valve comprising a casing having a permanently open inlet, a main outlet and a secondary outlet arranged to be opened and closed alternately by said main valve, and 75 openings in said casing communicating with said outlets and the respective ends of said cylinder.

2. In a water heating system, a water supply valve irresponsible to variations of water pressure, a gas supply valve, a thermostat in operative relation to the water supply valve to operate the same, and means for actuating the gas supply valve, said means comprising a cylinder, a piston therein, and a rod operatively connecting said piston to said gas valve, said water supply valve comprising a casing having a permanently open inlet, a main outlet and a secondary outlet arranged to be opened and closed alternately by said 80 main valve, and openings in said casing communicating with said outlets and the respective ends of said cylinder, and said rod comprising sections joined by a lost-motion device. 85

3. In a water heating system, a water supply valve irresponsible to variations of water pressure, a gas supply valve, a thermostat in operative relation to the water supply valve to operate the same, and means for actuating the gas supply valve, said means comprising a cylinder, a piston therein, and a rod operatively connecting said piston to said gas valve, said water supply valve comprising a casing having a permanently open inlet, a main outlet adapted to be closed by said valve and passageways communicating with the respective ends of said cylinder and adapted to be opened and closed to the water supply alternately by said main valve, and said rod comprising sections joined by an adjustable lost-motion device. 100

4. In a water heating system, a water supply valve irresponsible to variations of water pressure, a gas supply valve, a thermostat in operative relation to the water supply valve to operate the same, and means for actuating the gas supply valve, said means comprising a cylinder, a piston therein having a passageway therethrough and a spring pressed valve for said passageway, and a rod operatively connecting said piston to said gas valve, said water supply valve comprising a casing having a permanently open inlet, a main outlet adapted to be closed by said valve and passageways communicating with the respective ends of said cylinder and adapted to be opened and closed to the water supply alternately by said main valve. 110

5. In a water heating system, a water sup-

115

120

125

130

4
ply valve, a gas supply valve, means controlled by the water supply valve for actuating the gas supply valve, said means comprising a piston adapted to be actuated by the water, a rod connected to said piston and a rod connected to said gas supply valve, said rods being connected by an adjustable lost-motion device, and a thermostat mechanism constituting the exclusive means for 10 opening the water supply valve, said thermostat mechanism comprising an expansible tube in the water delivery pipe and a lever operatively connected to said expansible tube to be actuated thereby and mechanically 15 operatively connected to said water supply valve to actuate it.

6. In a water heating system, a water supply valve, a gas supply valve, means controlled by the water supply valve for actu-

ating the gas supply valve, said means comprising a piston adapted to be actuated by the water, a rod connected to said piston and a rod connected to said gas supply valve, said rods being connected by an adjustable lost-motion device, a thermostat constituting 25 the exclusive means for opening the water supply valve, said thermostat comprising an expansible tube in the water delivery pipe, a lever operatively connected to said expansible tube to be actuated thereby and 30 mechanically operatively connected to said water supply valve to actuate it, and a member adjustably mounted on said lever and constituting part of its operative connection with said tube.

Signed at St. Louis, Missouri, this 27th day of December, 1917.

WILLIAM F. STEWART.
